TRAFFIC CONTROLLING SYSTEM FOR
RAILROADSGeorge H. Wion, Rochester, N. Y., assignor to
General Railway Signal Company, Rochester,
N. Y.

Application January 26, 1932, Serial No. 588,890

7 Claims. (Cl. 246—3)

This invention relates to traffic controlling systems for railroads, and more particularly pertains to the remote control and indication of power operated track switches in interlocking systems.

The present invention proposes to combine a control and indication system for a railroad track switch in such a manner that a switch position repeating relay WP will not only indicate the position and locked condition of the track switch, but will also be governed in accordance with the correspondence of the track switch with the position of its control lever and the remote control relay. The present invention in part resides in the novel manner in which the above mentioned features are accomplished over a minimum number of line wires and without the use of a battery local to the outlying track switch.

Various other features, advantages and characteristic functions of the present invention will be in part obvious from the accompanying drawing, and in part pointed out, as the description of the invention progresses.

In describing the invention in detail, reference will be made to the accompanying drawing, which illustrates in a simplified and diagrammatic manner the circuits and parts of a switch machine control and indication system embodying the present invention, as applied to a single track switch.

With reference to the accompanying drawing, a railroad track switch TS is indicated as being operated by a switch machine SM, which may be of any suitable type such as disclosed, for example, in the patent to W. K. Howe, No. 1,466,903, dated September 4, 1923.

This switch machine SM preferably has associated therewith a suitable point detector contact mechanism PD, such as shown, for example, in the patent to C. S. Bushnell No. 1,517,236, dated November 25, 1924. For convenience in describing the present invention, the point detector PD is shown as having only movable contacts 5 and 6 with their associated fixed contacts. These contacts 5 and 6 are jointly operated by the track switch TS and the switch machine SM, as in the usual point detector contact mechanism, so as to assume normal or reverse extreme positions when the track switch is in normal or reverse positions respectively and locked by the switch machine, and so as to assume intermediate or mid-stroke positions whenever the track switch is being operated by the

switch machine or whenever the track switch is unlocked.

Associated with the switch machine is a control relay CR of the two position polarized type, that is, its contacts are operated to opposite positions by the application of potential of opposite polarities, and are held in their last operated positions by some suitable means such as a magnetic stick type structure or a suitable mechanical toggle device. One relay providing these characteristics has been disclosed for example in the pending application of J. F. Merkel Ser. No. 536,917, filed May 12, 1931.

A switch repeating or position indicating relay WP of the usual polar-neutral type is provided to indicate the position of the track switch in accordance with control circuits governed by the point detector contacts, the control relay CR and a switch machine control lever SML located in the tower. This polar neutral relay WP may be employed either at the track switch or in the tower for the selection of signal circuits, or the selection of various interlocking circuits in accordance with the usual practices, but so far as the present invention is concerned, it is immaterial whether the relay WP is in the tower or at the track switch, or just what specific circuits are controlled thereby. It is understood of course that some suitable traffic controlling devices are governed in accordance with its indications.

Preferably associated with the track switch TS is the usual detector track section having a track battery and the usual track relay as well as suitable signals for governing traffic thereover, but all of these devices and usual features of interlocking systems have been omitted for the sake of simplifying the disclosure of the present invention.

A suitable source of electrical energy is located in the tower of the interlocking plant for supplying energy to the various switches and other traffic controlling devices of the system. For this purpose a battery BT has been illustrated as supplying energy to bus wires 10 and 12 from which energy is taken both at the tower and at the switch machine for governing the track switch TS.

In the tower, a switch machine control lever SML is provided for governing the application of energy to the polarized circuits for operating the control relay CR and for suitably governing the WP relay to give the required indication of correspondence in accordance with the present invention.

Although the switch machine control lever SML has been shown as a simple free lever, it is to be understood that it may be of any suitable type known in the railway signalling art, as for example, the usual interlocking control lever having mechanical interlocking connecting it with the other devices in the system, or suitable electrical interlocking may be employed in the system. Also, suitable detector locking, approach locking and such other features of an interlocking system may be associated with the switch machine lever SML, as desired, so as to provide adequate protection for the operation of trains over the track switch TS, all of which will be well understood by those skilled in the art and need not be set forth in this connection.

It is believed that the nature of the invention, its advantages and characteristic features can be best understood with further description being set forth from the standpoint of operation.

Operation

With the track switch TS in a normal position and locked, the movable point detector contacts 5 and 6 are in normal extreme positions. As the switch machine lever SML is in a normal position, the control relay CR is energized with a polarity which causes its contacts to be actuated to normal right hand positions. This normal energizing circuit for the control relay CR is closed from the positive bus 10, through wires 15 and 16, contact 17 of lever SML in a normal position, line wire 18, wire 19, windings of control relay CR, wire 20, line wire 21, contact 22 of lever SML in a normal position, wire 23, to the negative bus 12. Although the current which flows in this circuit continually actuates the contacts of relay CR to right hand positions, it is to be understood that these contacts would remain in such positions should the control relay CR be deenergized.

With the control lever SML in a normal position, the contacts of the control relay CR in normal positions, and the point detector contacts in normal positions, a normal energizing circuit is completed for the switch position indicating relay WP from the positive bus 10, through wires 15 and 16, contact 17 of lever SML in a normal position, line wire 18, wire 24, polar contact 25 of control relay CR in a right hand position, wire 26, movable contact 6 in a normal position, wire 27, windings of relay WP, wire 28, movable contact 5 in a normal position, wires 29, 30 and 31, to the negative bus 12. The current which flows in this normal energizing circuit for the switch repeating relay WP causes its polar contacts to be actuated to left hand extreme positions and its neutral contacts to be picked up so that suitable circuits may be selected, as indicated by the legend on the drawing, in accordance with the correspondence of the track switch with the point detector contacts PD, the control relay CR and the control lever SML.

Whenever the operator desires to operate the track switch TS to the opposite position, (if it is safe to do so) he moves the lever SML to the opposite position which reverses the polarity applied to the control relay CR.

Assuming that the operator moves the lever SML to the reverse position, the reverse energizing circuit for the control relay CR is closed from the positive bus 10, through wires 15 and 32, contact 22 of lever SML in a reverse position, line wire 21, wire 20, windings of control relay CR, wire 19, line wire 18, contact 17 of control

lever SML in a reverse position, wire 23, to the negative bus 12. The current which flows in this circuit actuates the contacts of the control relay CR to left hand positions.

It is to be noted that the operation of the lever SML to a reverse position removes positive potential from the line wire 18 and places negative potential upon this wire, so that even before the control relay CR responds to the application of the opposite polarity, the normal energizing circuit for the relay WP is opened or discontinued, as the same potential is applied to both terminals of the relay WP, or in other words a shunt circuit is closed. After the response of the control relay CR, this shunt circuit is opened by the contact 25 in a left hand dotted line position.

It is to be further noted that the polar contact 33 governs the operation of the switch machine SM by applying positive potential from the bus 10 to the normal operating wire N when in the normal position and to the reverse operating wire R when in a reverse position, the circuit being completed from the switch machine to the negative bus 12 through the common wire 31, all of which has been illustrated conventionally rather than in detail, it being understood that suitable means is provided in the switch machine for opening the normal and reverse operating circuits and for closing the opposite operating circuit when the switch is in mid-stroke and when a particular operation has been completed.

The operation of polar contact 33 of the control relay CR to the reverse position energizes the reverse operating circuit of the switch machine SM as above mentioned, and causes the operation of the track switch TS to a reverse extreme locked position. During this operation while the track switch TS is unlocked, the movable contacts 5 and 6 of the point detector PD assume intermediate mid-stroke positions, in which positions a shunt circuit is completed for the relay WP from its left hand terminal through wire 23, movable contact 5 in an intermediate position, wire 34, movable contact 6 in an intermediate position, wire 27, to the right hand terminal of relay WP. This shunt circuit during operation of the track switch TS insures that the relay WP will give the proper indication of the unlocked condition of the track switch.

At the end of the reverse operation with the track switch locked, the movable contacts 5 and 6 assume reverse extreme positions in correspondence with the reverse positions of the contacts of the control lever SML and the control relay CR. This completes the reverse energizing circuit for the relay WP from the positive bus 10, through wires 15 and 32, contact 22 of lever SML in a reverse position, line wire 21, wire 36, polar contact 36 of control relay CR in a left hand position, wire 37, movable contact 5 of the point detector PD in a reverse position, wire 23, windings of relay WP, wire 27, movable contact 6 of the point detector PD in a reverse position, wires 38, 39 and 31, to the negative bus 12. The current which flows in this reverse energizing circuit for the indicating relay WP causes its polar contacts to be actuated to right hand reverse positions and its neutral contacts to assume energized positions, whereby the proper circuits may be selected in accordance with the reverse position of the track switch TS and the correspondence of the switch with the lever SML and control relay CR.

It is believed that the operation of the track switch TS back to a normal locked position will be readily understood by analogy to the operations and functions already described, as such 5 operation is merely an inverse function of the reverse operation.

A control and indication system for a railway power operated track switch has been shown and described wherein the indication relay not 10 only indicates the position of the track switch, but also the correspondence of the track switch with the control lever and control relay. This is accomplished over a minimum number of line wires for each track switch. It is to be understood of course, that two line wires, such as line 15 wires 18 and 21, are provided for each track switch for its control and indication besides the bus wires 10 and 12 which extend to all of the outlying track switches. This provides a safe 20 and economical system for the control and indication of a track switch.

Having thus described a control and indication system for railroad track switches as one specific embodiment of the present invention, it is desired to be understood that this form is selected 25 to facilitate in the disclosure of the invention rather than to limit the number of forms which it may assume; and, it is to be further understood that various modifications, adaptations and alterations may be applied to the specific form 30 shown to meet the requirements of practice, without in any manner departing from the spirit or scope of the present invention except as limited by the appended claims.

What I claim is:—

1. In a control and indication system for railroad track switches, a track switch, a switch machine having normal and reverse operating circuits, a polar control relay having contacts for governing said normal and reverse operating circuits by applying energy from a pair of bus wires, a control lever, two control wires connecting said control lever with said control relay, means for connecting said control wires to said bus wires respectively and for reversing said connections said means including said control lever, point detector contacts jointly operated by said track switch and said switch machine, a switch position indicating relay, and means energizing said indicating relay from one of said bus wires and said control wires alternately depending upon the position of said track switch in correspondence with said control relay and said control lever.

2. In a control and indication system for railroad track switches, a switch machine for operating a track switch, a pair of bus wires supplied with energy, a pair of control wires, a control lever for reversibly connecting said control wires to said bus wires, a control relay connected to said control wires and responsive to the direction of current flow therein to govern said switch machine to opposite positions upon the reversal of said control lever, point detector contacts operated jointly by said switch machine and the track switch, an indication relay, and means supplying energy to said indication relay from said bus wires in accordance with the position of said point detector contacts, said means including said control lever, said control wires and contacts of said control relay, whereby said indication relay indicates the position of the track switch and the correspondence of the control lever and control relay with such position of the track switch.

3. In a control and indication system for rail-

road track switches; a track switch; a switch machine for operating said track switch; a battery in a tower; two bus wires extending from said battery to said track switch; a control relay having contacts for governing the application of energy from said bus wires to said switch machine; two control wires extending from the tower to said control relay; a control lever in the tower for reversibly connecting said control wires to said bus wires; point detector contacts jointly operated by said track switch and said switch machine to normal, reverse or mid-stroke positions; an indication relay; and means including contacts on said control relay and said point detector contacts for energizing said indication relay from one of said bus wires and said control wires alternately depending upon the normal or reverse condition of said system; whereby said indication relay indicates the position of 10 said track switch and its correspondence with 15 said control relay and said control lever.

4. In combination; a distant track switch; a switch machine for operating said track switch; a polar relay for controlling said switch machine to assume a position corresponding to the polar position assumed by said polar relay and controlled over a pair of wires connected to a source of current in a local office; a lever in said office for polechanging said source on said pair of wires; a third wire leading from one terminal of said source to the location of said track switch; a polar indication relay; and means for energizing said indication relay by current of one polarity from said source and over one of said pair of wires and said third wire when said lever, said polar relay 25 and said switch machine assume one position, and for energizing said indication relay by current of the reverse polarity from said source and over one of said pair of wires and said third wire when said lever, said polar relay and said switch machine 30 assume the opposite position.

5. In combination; a distant track switch; a switch machine for operating said track switch; a polar relay for controlling said switch machine to assume a position corresponding to the polar position assumed by said polar relay and controlled over a pair of wires connected to a source of current in a local office; a lever in said office for polechanging said source on said pair of wires; a third wire leading from one terminal of said source to the location of said track switch; a polar indication relay; and means for energizing said indication relay by current of one polarity from said source and over one of said pair of wires and said third wire when said lever, said polar relay and said switch machine assume one position, and for energizing said indication relay by current of the reverse polarity from said source and over the other of said pair of wires and said third wire when said lever, said polar relay and said switch machine assume the opposite position.

6. In combination; a distant track switch; a switch machine for operating said track switch; a polar relay for controlling said switch machine to assume a position corresponding to the polar position assumed by said polar relay and controlled over a pair of wires connected to a source of current in a local office; a lever in said office for polechanging said source on said pair of wires; a third wire leading from one terminal of said source to the location of said track switch; a polar indication relay; means for connecting one or the other terminal of said polar indication 70 75

relay to said third wire in accordance with the position assumed by said switch machine, and means for connecting the unused terminal of said indication relay to the other terminal of said source only when said lever and said polar relay both assume a position corresponding to the position assumed by said switch machine.

7. In a control and indication system for railroad track switches, a track switch, a switch machine, a pair of bus wires, a pair of control wires, a control relay governed over said control wires for controlling said switch machine by energy

from said bus wires, a control lever for applying energy to said control wires, point detector contacts, an indication relay governed by said point detector contacts, means supplying energy from said bus wires and said control wires jointly for the energization of said indication relay in accordance with the position of said point detector contacts and the position of said lever, whereby said indication relay indicates the position of said track switch only if said lever assumes a corresponding position.
